Primary Examiner — Kevin Rudzinski(74) *Attorney, Agent, or Firm* — John D. Gugliotta, P.E., Esq.; Nicholas A. Mihalic, Esq.; Howard L. Wernow, Esq.(57) **CLAIM**

The ornamental design for a lint remover with spiral motif, as shown and described.

DESCRIPTION

FIG. 1 is a perspective view of a lint remover with spiral motif showing the preferred embodiment of my new design; FIG. 2 is a front elevational view thereof; FIG. 3 is a back elevational view thereof; FIG. 4 is left side view thereof; FIG. 5 is a right side view thereof; FIG. 6 is a top plan view thereof; and, FIG. 7 is a bottom plan view thereof. Dashed lines in the figures represent a handle of a lint roller and form no part of the present invention.
